UNITED STATES PATENT OFFICE.

JOHN H. STRINGHAM, OF JERSEY CITY, NEW JERSEY.

APPARATUS FOR IGNITION IN EXPLOSIVE-ENGINES.

1,243,002.

Specification of Letters Patent. Patented Oct. 16, 1917.

Application filed June 26, 1914. Serial No. 847,395.

To all whom it may concern:

Be it known that I, JOHN H. STRINGHAM, a citizen of the United States, residing in Jersey City, in the county of Hudson and

5 State of New Jersey, have invented certain new and useful Improvements in Apparatus for Ignition in Explosive-Engines, of which the following is a specification.

This invention relates to apparatus for 10 ignition in explosive engines and has for its object the provision for self-timing ignition, of such efficiency as to produce greatly improved combustion, embodied in a self-contained apparatus requiring no additional 15 mechanical attachment or disarrangement of the engine and adapted to inexpensive manufacture.

Figure 1 is a plan view of my device.

Fig. 2 is an elevation in perspective.

20 Fig. 3 is a sectional elevation on the line 3-3 of Fig. 1.

In the accompanying drawing, a preferred form of apparatus is illustrated. 1 represents the cylinder head to which (as, for 25 example, through the valve chamber) is screwed or otherwise fitted the piece 2. The pieces 3 and 4 are held together and to the piece 2 by screws 5. This construction is particularly valuable because it enables all 30 parts to be made by direct work in the easiest and cheapest fashion and permits of easy assemblage and access to any of the parts which may require attention. The invention may, of course, be embodied in apparatus 35 not possessing this feature of construction and otherwise different in form from the particular embodiment illustrated in the drawings. Opening into the cylinder is a valve 6 adapted to be opened by the 40 compression in the cylinder, provided with means, as a spring 7, to keep it closed, except when the pressure against it is sufficient to open it. The means for holding the valve 6 closed are preferably adjustable, as, for 45 example, in the drawings the tension of the spring 7 may be adjusted by the screw 8. The purpose of providing this adjustment of the closing means is in order that the valve may be opened only when the pressure 50 of the compression against it is near its highest point. In the preferred form the valve is a double acting valve, seating itself at its top as well as its bottom, so as to prevent the escape of gas except into the 55 pass 9. Connected with the pass 9 is a chamber 10, which is preferably lined with,

and contains, heat resisting material. Said chamber is provided with a second valve 11, preferably constructed like the valve 6, and provided with means for holding it 60 closed, as, for example, the tension of the spring 12, which, like the spring 7, is preferably adjustable. The tension of the spring 12 is made higher than that of the spring 7 and preferably just below the greatest 65 force of the explosion in order to prevent loss of power. The valve 11 is preferably provided with a hole or passage 13, making a small slide valve, which opens when the pressure on the valve 11 is light (as when 70 the engine is running free) and is automatically closed by the force of a heavier explosion.

The operation is as follows:—The compression of the cylinder opens the valve 6, 75 but is insufficient to open the valve 11. The explosion (first ignited by other means, as a spark plug) opens the valve 11 and some of the gases escape to the exhaust. When the explosion pressure is slightly reduced 80 the valve 11 closes, trapping some of the products of combustion in the chamber 10, which remain in that chamber after the closing of the valve 6 before or upon the opening of the exhaust of the engine. 85 When the compression in the cylinder becomes sufficient again to open the valve 6, the gases trapped in chamber 10 ignite the compressed charge and the operation is repeated.

90 By the arrangement shown the timing of the ignition is automatic after the springs have been once set for any particular engine, because when the load on the engine is heavier more gas is sucked into the cylinder, so that the pressure opening of the valve 6 comes sooner and the effect is accordingly equivalent to advancing the spark.

95 It is apparent that various modifications may be made without departing from the 100 spirit or scope of the invention.

I claim:—

1. An ignition device for explosive engines comprising a cylinder, a chamber communicating with the cylinder and atmosphere, respectively, by passages, a valve controlling the passage to the cylinder adapted to be opened by the force of the compression, and a valve controlling the passage to the atmosphere adapted to be opened by the 110 force of the explosion.

2. An ignition device for explosive en-

- gines comprising a trap for the products of combustion opened to the explosion chamber by means of a valve actuated by the compression pressure therein.
5. An ignition device for explosive engines comprising a chamber having a connection with the cylinder of the engine controlled by a valve actuated by the pressure therein, and another connection with the atmosphere controlled by a valve actuated by a higher pressure.
10. An ignition device for explosive engines comprising a chamber adapted to hold products of combustion communicating with the cylinder, a valve between said chamber and the cylinder of the engine, actuated by the compression pressure in the cylinder, and adjustable means for holding said valve closed until a certain degree of pressure in the cylinder is reached.
15. An ignition device for explosive engines comprising a chamber, an automatic valve between said chamber and the cylinder of the engine held normally closed by a spring, and another automatic valve between said chamber and the atmosphere held normally closed by a spring of higher tension.
20. An ignition device for explosive engines having a chamber adapted to hold products of combustion and a connection between said chamber and the cylinder, a double-acting valve controlling said connection actuated by pressure and adapted to seat itself at its top while open at its bottom.
25. An ignition device for explosive engines having a chamber adapted to hold products of combustion, a connection be-

tween said chamber and the atmosphere, a valve controlling said connection adapted to be raised by pressure in said chamber, and having a passage which is closed when the valve is in lowered position and closed when the valve is in raised position but open when the valve is in intermediate position.

40. An ignition device comprising a double acting compression valve and double acting explosion valve, a bottom piece containing a chamber, a bottom seat for the compression valve and a passage to said chamber therefrom; a middle piece containing a bottom seat for the explosion valve and the top seat for the compression valve; a top piece containing the top seat for the explosion valve and means for holding said valves normally closed; and bolts holding said pieces assembled.

45. An ignition device comprising a double acting compression valve and double acting explosion valve, a bottom piece containing a chamber, a bottom seat for the compression valve and a passage to said chamber therefrom; a middle piece containing a bottom seat for the explosion valve and the top seat for the compression valve; a top piece containing the top seat for the explosion valve and means for holding said valves normally closed; and bolts holding said pieces assembled.

50. An ignition device comprising a double acting compression valve and double acting explosion valve, a bottom piece containing a chamber, a bottom seat for the compression valve and a passage to said chamber therefrom; a middle piece containing a bottom seat for the explosion valve and the top seat for the compression valve; a top piece containing the top seat for the explosion valve and means for holding said valves normally closed; and bolts holding said pieces assembled.

55. An ignition device comprising a double acting compression valve and double acting explosion valve, a bottom piece containing a chamber, a bottom seat for the compression valve and a passage to said chamber therefrom; a middle piece containing a bottom seat for the explosion valve and the top seat for the compression valve; a top piece containing the top seat for the explosion valve and means for holding said valves normally closed; and bolts holding said pieces assembled.

60. An ignition device comprising a double acting compression valve and double acting explosion valve, a bottom piece containing a chamber, a bottom seat for the compression valve and a passage to said chamber therefrom; a middle piece containing a bottom seat for the explosion valve and the top seat for the compression valve; a top piece containing the top seat for the explosion valve and means for holding said valves normally closed; and bolts holding said pieces assembled.

65. An ignition device comprising a double acting compression valve and double acting explosion valve, a bottom piece containing a chamber, a bottom seat for the compression valve and a passage to said chamber therefrom; a middle piece containing a bottom seat for the explosion valve and the top seat for the compression valve; a top piece containing the top seat for the explosion valve and means for holding said valves normally closed; and bolts holding said pieces assembled.

70. An ignition device comprising a double acting compression valve and double acting explosion valve, a bottom piece containing a chamber, a bottom seat for the compression valve and a passage to said chamber therefrom; a middle piece containing a bottom seat for the explosion valve and the top seat for the compression valve; a top piece containing the top seat for the explosion valve and means for holding said valves normally closed; and bolts holding said pieces assembled.

JOHN H. STRINGHAM.
